WEB SPLICING APPARATUS

Oscar Charles Roesen, Eastchester, N. Y., assignor to Wood Newspaper Machinery Corporation, New York, N. Y., a corporation of Virginia

Application March 14, 1932, Serial No. 598,736

9 Claims. (Cl. 242—58)

This invention relates to the splicing of a running web to a rotating fresh web roll chiefly for printing presses.

The principal objects of the invention are to provide for the keeping of the fresh web roll free from adhesive on its outer surface while it is being speeded up so that it can be rotated by moving means in contact with its surface without danger of getting the adhesive on the said 5 moving means and to permit the use for rotating this roll of the ordinary running belts which are normally used for tension, and to provide mechanism for supplying the adhesive to the running web or running roll or both at the proper 10 moment.

Other objects and advantages of the invention will appear hereinafter.

Reference is to be had to the accompanying drawings, in which—

Fig. 1 is an end view of a well known type of magazine reel used for splicing with a preferred embodiment of this invention applied thereto;

Fig. 2 is an elevation thereof, and

Fig. 3 is an end view showing a modification 25 of the method of applying the adhesive.

In the forms shown in Figs. 1 and 2 is illustrated, as stated, an ordinary three-armed spider constituting part of a rotary reel for supporting the fresh web roll S and the running roll R. Tension belts 1 are employed passing over a series of idlers. These belts are operated by a series of pulleys using power from the press to drive the belts in the proper proportion to the speed of the web. Weights 2 are shown to support an idler pulley in a loop of each belt 1 to keep the belts taut. These features are all well known.

At the end of the reel comprising the spider above mentioned is mounted a cam bracket 3. It provides a pivotal mounting for a shaft 4 to which is pinned an arm 5 whose free end is pivotally connected to a link 6. To the other end of the link 6 is pivoted a nozzle 7 made up of a container for the adhesive and a plurality of open-ended projections, each one forming a nozzle and all of them together constituting means for applying the glue or other adhesive throughout the width of the web. This nozzle may be provided with a source of compressed air or the like for forcing the material out of it when desired and an air pipe 20 is shown.

The oscillating of the shaft 4 is accomplished by a worm wheel 8 and a gear segment driven 55 from any desired source of power that is reversi-

ble and obviously it imparts motion to the nozzle 7 between the full and dotted line positions shown in Fig. 1.

Pivoted to the nozzle 7 is an arm 9 which is centered on the shaft 10 of the reel. A stud 11 on the arm 9 constitutes a pivot and, as the arm 9 is centered to the shaft 10, this stud 11 describes an arcuate path around this shaft as nozzle 7 is brought up to operating position.

A stationary cam path 19 is provided in which 10 a cam roller 18 operates. This roller 18 is pivotally carried on the nozzle structure but on the opposite side of the stud 11 from the nozzle opening. As the arm 9 rotates, this roller 18 follows the cam and controls the motion of the 15 nozzle about its pivot 11 so as to direct it at the proper angle to project the adhesive in the desired direction. This link and arm connection is duplicated at the other end of the reel and on each arm of the spider is carried a pivoted 20 arm 12 which is spring-pressed by a spring 13 in a counterclockwise direction, the necessary poppets being used to connect the spring with the reel and the arm 12.

On each reel arm also is pivoted a latch 14 25 adapted to hook over a projection 15 on the arm 12. This latch is pressed by a spring in a clockwise direction and is adapted to be released by the operation of a solenoid 16 at the desired time. When released, the spring 13 swings the arm 30 and its end operates against the arm 17 of the oscillating valve carried in the nozzle thereby opening the nozzle and ejecting adhesive. This action is so timed as to eject the adhesive at the time of the rotation of the fresh roll S just 35 before the splice is to be made.

The forward edge of the roll S is cut to the proper shape and held down by a mild adhesive to allow the roll to rotate up to web speed until it is time to make the splice.

The spare roll S is brought by the rotation of the reel up against the running web having belts 1 behind it and is rotated therefore up to web speed and held at that speed. Now, at the proper time the solenoid 16 is operated either manually or automatically, releasing the arm 12. This action of the arm 12 opens the nozzle, permitting the discharge of the proper amount of adhesive. This adhesive is sprayed or forced out between the web and the running roll R and may 50 be applied to the surface of either or both.

This method of applying adhesive between the forward end of the fresh roll and the running web itself, on the incoming side of the roll, for engaging the splice insures that the adhesive shall 55

be applied just prior to splicing and while the fresh roll is running at web speed. Therefore, there is no necessity for having any adhesive on the roll S while it is being speeded up and 5 no danger of getting adhesive on the web prematurely.

In the modification shown in Fig. 3, the nozzle 7 instead of shooting adhesive directly out of the nozzle, is provided with a small sheet of material 28, such as paper, which has been previously pasted and is still damp over the end of the nozzle. This sheet is shot by this nozzle in between the running web and the running roll. This serves to apply the necessary compound to 10 attach the free end of the web roll to the running roll S and make the splice.

Although I have illustrated and described only two forms of the invention, I am aware of the fact that modifications can be made therein by any 20 person skilled in the art without departing from the scope of the invention as expressed in the claims. Therefore, I do not wish to be limited to all the details of construction herein shown and described, but what I do claim is:—

25 1. In a web splicing apparatus, the combination with means for supporting a web roll and a web tangent thereto and in connection therewith, of a nozzle containing an adhesive located in the angle between them on the side from which the 30 web is running.

2. In an apparatus for splicing a running web roll and a running web in contact, the combination of a nozzle, and means for swinging said nozzle into a position adjacent to the roll and 35 between the roll and web when it is desired to make the splice.

3. In an apparatus for splicing a rotating web roll and a running web moving in contact, the combination of a movable nozzle located in the 40 space between the web roll and the web running toward it, means for supplying said nozzle with an adhesive under pressure, and means for moving the nozzle into a position in said space in which it will direct the adhesive toward the point 45 of the angle between the roll and the web.

4. In a web splicing device, the combination of a nozzle located between a fresh web roll and a

running web having means for ejecting adhesive, means for supporting the nozzle in movable position, and means for moving the nozzle as a whole back and forth.

5. In a web splicing device, the combination of a nozzle located in the angle between a fresh web roll and a running web having means for ejecting adhesive, means for supporting the nozzle in movable position, means for moving the nozzle as a whole back and forth, and means for swinging 10 the nozzle on an axis as it moves.

6. In a web splicing device, the combination with a nozzle pivotally mounted, an arm supporting the pivotally mounted nozzle, a reversible shaft, means for operating the shaft in either 15 direction, connections from said shaft to the nozzle for moving the nozzle back and forth, an arm connected with the nozzle and having a projection, and a stationary cam for receiving said projection and controlling the position of the 20 nozzle as it moves back and forth.

7. In a web splicing device, the combination with a support for the running roll and fresh roll adapted to be located in such position that the web contacts with the fresh roll at the time of 25 splicing, a nozzle adapted to project adhesive into the angle between the web and roll, means for moving said nozzle, a valve for controlling the nozzle, and means for operating the valve.

8. In a web splicing device, the combination with a support for the running roll and fresh roll adapted to be located in such position that the web contacts with the fresh roll at the time of splicing, a nozzle adapted to project adhesive into the angle between the web and roll, means for moving said 35 nozzle, a valve for controlling the nozzle, an arm on the support having means for operating the valve, a latch for holding the arm in inoperative position, a solenoid for releasing the latch, and a spring operative upon release of the latch for 40 moving the arm into position to open the valve.

9. In a web splicing device, the combination of means for speeding up the fresh roll and means for spraying adhesive on the fresh roll and on the running web simultaneously.

OSCAR CHARLES ROESEN.
